MEASURING TAPE CASE

Francesco G. Collura, New York, N.Y., assignor to
Keuffel & Esser Company, Hoboken, N.J., a corpora-
tion of New Jersey

Application July 18, 1958, Serial No. 51,844

Term of patent 14 years

(Cl. D52—1)

Fig. II

Fig. I

Fig. III

Fig. IV

Fig. V

Fig. VI

Fig. I is a front elevational view of a measuring tape case showing my new design;

Fig. II is an end elevational view thereof as seen from the left of Fig. I;

Fig. III is an end elevational view as seen from the right of Fig. I;

Fig. IV is a rear elevational view;

Fig. V is a top plan view; and

Fig. VI is a bottom plan view thereof.

I claim:

The ornamental design for a measuring tape case, as shown.
